Primary Examiner — Sheryl Lane*Assistant Examiner* — Calvin E Vansant(74) *Attorney, Agent, or Firm* — Stetina Brunda Garred & Brucker(57) **CLAIM**

The ornamental design for a pet carrying bag, as shown and described.

DESCRIPTION

FIG. 1 is a top, front perspective view of the pet carrying bag of the present invention showing my new design;

FIG. 2 is a top plan view thereof;

FIG. 3 is a front elevational view thereof;

FIG. 4 is a back elevational view thereof;

FIG. 5 is a bottom plan view thereof; and,

FIG. 6 is a right side elevational view thereof, the left side elevational view being a mirror image of the right side elevational view.

The broken lines in FIGS. 1-6 represent stitching and form part of the claimed design.
